ORNAMENTING MACHINE

Benjamin W. Freeman, Cincinnati, Ohio

Application April 5, 1938, Serial No. 200,217

55 Claims. (Cl. 101—316)

This invention relates to machines for use in the manufacture of boots and shoes, and more particularly to combined marking and cutting machines adapted for operations upon skins, upper blanks, fitted or closed uppers and the like, in which the work is marked with ink, pigment, or its equivalent, at the same time or as part of a cycle of operations, during which the work is also ornamented by perforating or cutting out a design therein, the cutting and marking preferably being performed as a single factory operation.

The present invention is directed to improvements upon devices and machines for effecting the mentioned operations, as described and claimed in the patents to Benjamin W. Freeman, No. 2,084,335, dated June 22, 1937, and Benjamin W. Freeman et al., Reissue No. 20,294, dated March 16, 1937, and the co-pending application of Benjamin W. Freeman, Serial No. 83,796, filed June 5, 1936, to which reference is hereby made.

These machines are of a type intended for use as "universal" cutout and marking machines, specifically intended for work on shoes, leather, and shoe materials, where the work is of widely varying contour and design, the machines being designed to operate, not only upon flat material, but also to perform operations on other than flat work, such as closed and fitted uppers or other types of ring-like work.

Objects of the invention include the formation of ornamental designs in the work, by the application of a stamped or printed marking which may simulate stitching, or may take the form of a design, or by the formation of ornamental cutouts in the work, or by combinations of both markings and perforations or cutouts; and the accomplishment of the marking and cutting operations either simultaneously or during a continuous cycle of operations.

Reference to stamped or printed markings is made herein because of its universal adaptation to all types of leather; however, the present invention is likewise readily adaptable to the production of other forms of marking, e. g., impression or indentation of the work. It is a further object herein to provide means for changing from one form of marking to another by a slight adjustment, and without necessitating change of any part of the machine.

A still further object contemplates the application of markings which may be used to form a printed ornamental pattern, or as a guide for subsequent operations on the shoe parts, such as aligning the parts relative to each other,

stitching, etc., the markings being applied at such a time and in such a location with reference to the cutouts as to insure accuracy in the subsequent operations with relation to the cutout portions of the work.

While it is contemplated further that the marking device may be combined with, or form a part of the conventional stripper plate which is normally designed for stripping the work from the cutting edges of the die, it is also an object to provide a marking device which may operate in conjunction with the cutting or perforating elements of the die without in any substantial measure applying a stripping pressure to the work.

An automatic inker is provided for the application of ink or equivalent marking medium, to the marking portions of the die, and by means of which ink is applied to the die with every stroke of the plunger, i. e., in timed relation thereto. The invention contemplates, among its objects, an ink roll organization by means of which the level of the ink roll can be varied, control of pressures of the roll against the die, for light or heavy marking, is attained, and ink is replenished and supplied to the ink roll for transfer to the die, with every stroke of the plunger.

Various safety mechanisms assuring a predetermined cycle of operations, and designed to prevent injury to an operator or to the work by preventing premature, delayed or inaccurate operations form a feature of this invention.

As described in the aforesaid copending applications, and illustrated herein, a preferred embodiment of the machine has a power driven plunger movable through a relatively vertical plane, the plunger serving to mount a work support on which the work may be accurately positioned by means of suitable gaging devices.

A die which is relatively fixed insofar as vertical movement toward the work supporting plunger is provided, and this die is arranged to move into and out of an operative relation to the plunger, the movements however, being confined to a substantially horizontal plane in the illustrated embodiment. Means are also provided for retaining the die against movement in any direction should it be desired to so operate the machine.

In order to effect the movements of the die, there is provided a carriage which is actuated electrically, preferably through the medium of an electro-magnetic clutch, whereby instant and complete control of the carriage movements and position are obtained.

A backing medium of paper, or its equivalent, is provided, and fed between the work and the support, one of the objects of this invention being to provide an improved mechanism for carrying and actuating the feed rolls for such backing medium.

It has been the practice right along to construct cutout machines so that the paper feed mechanism is connected to the crank shaft of the machine, and as a consequence the feeding of the paper takes place during rotation of the crank shaft. The crank shaft in a cutout machine actuates the plunger by means of which the cutters of the die are forced through the work, and it follows that the paper feed takes place during the movement of the plunger. However, the backing medium must not be fed while the die is contacting the work and therefore the feeding of the paper must take place in only a part of the cycle. Most of these machines operate at about 200 to 350 R. P. M. so that there are many limitations to such structure, and an important object of the present invention is to provide a paper feed which is operated and controlled independently of the crank shaft, or other operating parts of the machine, and not limited by the cycle period thereof.

In the preferred form illustrated herein, the paper feed mechanism is driven by the same motor that actuates the plunger, but it will be noted that an intervening clutch is provided which might be termed a magnetic paper feed clutch and this makes it possible to use the power at any designated time.

The paper feed parts move so fast that there is a great deal of wear and breakage. The amount of paper that can be fed in the short time available is limited and with large dies on certain machines of this general type it has been impossible to provide sufficient feed for the paper, so the operator was obliged to treadle the machine a time or two without the die in operative relation to the plunger. In other cases, the feeding of the paper is dispensed with, and instead of using a roll of backing paper in a customary manner, pieces of the backing material are cut to a suitable size to accommodate the die, and handled separately in this manner during each cut, a separate piece of backing paper being used each time or in some cases several times.

With an independent feed, it is possible to regulate the amount and time of feed, and also to provide a smooth even feed, and accordingly objects of the invention include a mechanism for feeding a sufficient amount of paper as may be required, and for feeding the paper without a jerky movement, through a nice smooth action.

The feed may take place while the operator is moving the work, and during a portion of the cycle when the plunger is not operating at all.

Still another object contemplates a control mechanism for the paper feed through the medium of electro-magnetic clutches whereby the timing and length of feed may be regulated to a very fine degree.

Gauging devices are provided for aligning the work relative to the die and these gauges may be carried by the work support, by the die, or otherwise interposed between the work supporting surface and the die. The gauging device may take the form of a mask effective to clamp or hold the work in its aligned position; in fact, it is contemplated that a mask or clamp having no gauging function may cooperate with any desired type of gauge for this purpose.

A single control, as a treadle or its equivalent, is preferably utilized for the mechanism by means of which the die may be moved into an operating position, the marking elements of the die inked, 5 the main clutch of the machine released, the work support and plunger raised to effect an operation on the work, and return, and the die thereafter moved to a position away from an operator who may then remove the work from the machine.

The broad principles and mechanisms for accomplishing these several results under a single control are illustrated in the aforesaid patents and application, and the improvements herein described aim toward simplification of such mechanisms and improvement in certain constructions going to the make up of the complete machine, such as the backing paper support and feed mechanism, adjustments in the inking roll mechanism, control of the plunger by movements of the die carriage together with control of the die carriage by the plunger, in the mode of attaching and locking a die in the machine, together with safety means preventing operation 15 of the machine at all times, except when the die is accurately positioned and locked in such position, in improvements in the die carriage driving mechanism, together with certain adjustments by means of which accuracy to a fine degree in the travel of the die may be accomplished regardless of wear in the machine, and in improvements upon the automatic control means synchronizing operation of the various mechanisms.

It is an object to provide electrical controls for the various moving parts which are in themselves under the control of certain of the moving parts, e. g., the paper feed is regulated in its timing and duration by an electro-magnetic clutch, the current for which is under the control of the die carriage.

While the present invention relates specifically to improvements over the machine of the said patents and application, the general aims and objects as set forth therein are however, retained.

Ornamenting machines for forming cutouts in a work piece, or for making same, or for effecting both operations are of course known, but the present machine is designed to meet increasing demands of work and operating pressures without increasing the size of the machine itself to an impractical degree.

In commenting upon the universal features of this machine it should be noted that the structure is readily adaptable to various types of dies and to various operations. For example, the die may be mounted to cut up or down, or in lieu of a die mounted within the machine, a self-contained auxiliary type of die and paper feed mechanism may be utilized by placement of such auxiliary unit upon the work support, which will then act to move the auxiliary unit with the work thereon toward the head of the machine, which head will function as a resistance or reaction member.

Another improvement contemplates automatic control of movements of the operating plunger, die carriage, feed of backing medium, and other portions of the machine, whereby to obtain a more perfect synchronism and accurate relation of parts.

Among the main or principal features of the preferred form of machine are a substantial difference in the arrangement of parts over prior

art machines which endeavor to obtain similar results, i. e., the operating plunger partakes of a movement through a generally vertical plane, the die unit remaining fixed, insofar as the plane of travel of the work support is concerned, while being movable through a substantially horizontal plane into and out of operating position.

Such arrangement permits maintenance of necessary clearance between the die and work support, facilitates changing of dies in the machine, fitting of the work into proper position, and inking of the marking elements. It also permits a decrease in the operating stroke of the plunger, as compared with prior art machines, and avoids excessive inertia in moving parts. Furthermore, where it was essential from the standpoint of safety in many prior art machines, that the operator wait until all moving parts had come to rest, with the present apparatus the operator may be handling the work in perfect safety even though the die is still moving to its inoperative position after cutting or marking the work.

One of the most important features of the present invention relates to the mechanism and method of stripping the work from the die. Conventional strippers include some mechanism directly associated with the die unit, e. g., a stripper plate mounted on springs which serve to normally maintain the plate in a position slightly in advance of the cutting edge of the die. The spring pressure must be so adjusted as to accommodate varying thicknesses of leather or other material upon which the die is working and difficulties arise in this connection, particularly when marking edges are placed on the stripper. Thus if the spring pressure is adjusted to mark and strip properly a light piece of calf-skin, it would probably injure a heavy piece of leather. Obviously, when the material is thick, the stripper will be depressed by the material, more than would be the case with thin leather. Varying pressures are required with different characters of leather as well as with different thicknesses, and as the number of cutouts or perforations in a piece of work is increased, the need for greater pressure likewise increases, and such pressures are very difficult of attainment with the conventional stripping devices now in use.

These difficulties and objections have been largely overcome by my patented methods and devices for ink marking and cutting, mentioned in the aforesaid application, but even they are limited as to the treatment of extremely heavy work, requiring heretofore unheard of pressures in such machines. In other words, some desired types of work require pressures too great for satisfactory stripping.

In the solution of these problems, particularly that of extreme pressures, the present invention contemplates a stripping mechanism wherein the pressure is applied by an arrangement independent of any particular die, this being accomplished by building a stripper pressure applying mechanism into the machine, as distinguished from supplying an individual die with a self-contained, complete stripping arrangement. The usual stripper plate, mounted in advance of the cutters, is retained.

To the attainment of the foregoing and other objects which will appear as the description proceeds, reference may be made to the accompanying drawings, in which:

Fig. 1 is a side elevation of a preferred form of machine;

Fig. 2 is a side elevation partly in section of the opposite side from that shown in Fig. 1;

Fig. 3 is a front elevation thereof;

Fig. 4 is a rear elevation of the lower portion of the framework of the machine;

Fig. 6 is a front elevation of the ink applying mechanism;

Fig. 7 is a side elevation partly in section of the driving mechanism for the die carriage;

Fig. 8 is a top plane partly in section of the carriage driving mechanism; and

Fig. 9 is a rear elevation thereof.

General organization

Referring now more specifically to the drawings in which like reference numerals designate like parts, there is disclosed a main frame or housing 10 mounted upon a base designated generally at 11. A work supporting plunger 12 is mounted in the frame for vertical reciprocation, being actuated in the manner described in the patents and application mentioned above. A die holder or carriage 13 is mounted for sliding movement upon a track or guideway 14-14 for horizontal reciprocating movement from an inoperative position at the rear of the machine to an operating position over the work support. Suitable anti-friction bearings will preferably be supplied for mounting the carriage upon the track.

Various styles of die may be mounted upon the under face of the die carriage, and suitably secured in place. Examples of such dies and the details of mounting and securing the die will be found in the aforementioned patents.

Power may be supplied to the machine through a fly wheel pulley 16 which is mounted for free rotation upon the plunger actuating crank shaft 17. The pulley 16 may be driven from any convenient source of power, a motor 18 being illustrated. The motor is provided with a pulley 19 which is connected by a belt or belts 20 to the fly wheel 16. The crank shaft 17 will be connected to actuate the plunger 12, when clutched to the fly wheel in a manner hereinafter described.

The die carriage may be conveniently driven by a compact driving unit designated generally at 22 mounted at the upper rear of the machine on a shelf or bracket 23, which unit is controlled and actuated as hereinafter described.

Paper feed mechanism

The paper feed mechanism, including the driving mechanism for the feed rolls, is best illustrated in Figs. 1 to 4. The paper feed in all machines of this nature must be in some manner synchronized with the other operating parts of the machine such that a predetermined amount of paper is fed for each cycle. Heretofore the source of power has usually been the machine drive or main crank shaft. The present invention differentiates by having an independent drive and by being driven from an independent source of power, that is, not directly from the crank shaft of the machine. This eliminates a jerky feed, and permits control of the length of feed and the time that the feeding of the paper takes place in the cycle of operation of the machine.

The driving mechanism for the feedrolls includes a tube 25 mounted at the side of the frame 10 (Fig. 2), which extends to a clutch housing 26. The tube 25 is mounted in a bracket 27

by means of a bearing 28 in which it can rock, and slide a little. The bearing 28 is provided with a stub shaft 29 which is directly mounted in the bracket 27, being freely rotatable or oscillatable therein. With this arrangement the tube 25 would oscillate about the stub shaft 29 as a pivot and also slide slightly in the bearing 28 to accommodate the rocking movement about the stub shaft.

Mounted at the front end of the clutch housing 26, i. e., on the opposite side thereof from the tube 25, is a gear casing 30, and the tube, clutch housing, and gear casing are rigid with each other as a unit rockably mounted in the bracket 27.

A drive pulley 31, located at the rear end of the tube 25 is secured to a shaft 32 carried by suitable bearings within the tube, and extending into the clutch housing 26.

An electro-magnetic clutch therein, of a generally conventional type, has its hub 33 secured to the end of the shaft 32, and this hub serves to house the usual coil, and to mount commutator rings 34. Suitable contacts 35 are mounted in the housing for engagement with the commutator rings. A clutch plate 36 is provided on the combined hub and coil housing 33.

A shaft 37 is aligned with the shaft 32 and extends into the clutch housing from the side opposite the shaft 32, and this shaft 37 serves to mount a second clutch plate 38, whereupon when current is supplied to the coil of the clutch, the plate 38 will be magnetically drawn into engagement with the plate 36. The shaft 37 projects out of the clutch housing and terminates in a head 39. Between the head 39 and a shoulder 41 on the gear casing 30 is a spring 42 which normally pushes the shaft 37 and clutch plate 38 away from the plate 36, the plate 38 being drawn into engagement with the plate 36 against the action of the spring 42 when current is supplied to the clutch.

Splined upon the shaft 37 is a worm 43 which meshes with a worm wheel 44. The worm wheel 44 is keyed to a feed roll drive shaft 45 which extends across the front of the machine and serves to mount and drive the main feed roll 46 (Fig. 3). A second feed roll 47 is suitably geared, as at 48, to be driven by the shaft 45. The gear 45 is supported by bearing brackets 49-49, rigid with the plunger 12 and from which depend rigid bearing arms 51-51.

The roll 47 is supported by bearing arms 52 pivoted to the brackets 49, and said roll is normally urged toward the main feed roll 46 by resilient spring mountings 53 for the arms 52. A rod 54 is positioned to extend between the arms 52 and abutments 55 on the brackets 49. This rod is provided with flattened portions at the points where it extends between the pivoted bearing arms 52 and the abutment 55, and terminates in a handle 56 by means of which it may be rotated. It follows that by rotation of the rod 54 through the medium of the handle 56, the flattened portions will be turned away, and the full diameter of the rod brought into position between the arms 52 and the abutments 55, thereby separating the same, and separating the two feed rolls 46 and 47 slightly, to permit insertion of the backing web and adjustment of tension, etc. Adjustment of the spring devices 53 will effectively vary the tension of the paper web passing between the feed rolls.

The lower end of the rigid bearing arms 51 serve to mount an idler roll 57, for guiding the 75

web of backing material in its path through the machine. Preferably the paper web will be supported on an idler shaft 50 at the rear of the machine, and a run or web thereof will pass forwardly through the machine across the work support and back to a rewinder shaft 58 which operates intermittently in conjunction with a step by step feed of the paper.

It will be noted that the feed roll assembly, including the idler roll, gearing between rolls, and the regulating or adjusting devices, is mounted on the plunger 12 and will move therewith. This assembly is, of course, rigid with the worm gearing, clutch and drive shaft at the side of the machine, and movement of this driving mechanism with the plunger and feed roll assembly is accommodated by the pivotal mounting of the tube 25. In other words, with each movement of the plunger, the entire feeding mechanism for the backing material will be given a movement through the extent of movement of the plunger.

Adjustments of the amount of feed of the paper are effected by varying the time that current is fed to the magnetic clutch through the leads or contacts 35. The control of current feed is accomplished as follows: extending along the path of movement of the die carriage is a bus bar mounting 59, and this mounting is pivoted at 60 at the rear of the frame 10. The forward end of the mounting 59 is engaged by a dog pointed adjusting screw 61 threaded through the frame 10, and which terminates outside of the frame in a knurled knob 62. A spring 63 connected to the frame 10 and to the mounting 59 maintains engagement between the mounting and the point of the screw 61 from which it can be seen that one end of the mounting may be swung toward and from one side of the die carriage. A pair of spaced, connected contacts 64 located on the die carriage, serve as a means to bridge the bus bars on the mounting 59, and by suitable connections from the bus bar, current will flow to the clutch contacts 35. Such connections would include a lead from one bus bar to a control switch 151, hereinafter described and a lead from the other bus bar to one of the clutch contacts 35. The other clutch contact will of course be properly connected to complete the circuit.

It will be obvious that the contacts 64, being mounted on the die carriage 13, will always move in a straight line, while at the same time the bus bar mounting 59 may be positioned in various lateral angular relations thereto. From this, it will be evident that the duration of contact between the contact elements 64 and the bus bar mounting 59 can be varied as desired, thus varying the length of time that current flows to the clutch contacts 35, and consequently varying the timing and operation of the magnetic clutch 36-38. Variation in the operation of the clutch naturally varies the amount of paper which is fed, and by means of the very slight adjustment through the dog pointed screw 61, the paper feed may be controlled, both in duration and time of starting.

The contacts 64 are preferably spring mounted for proper engagement with the bus bar mounting 59, and are headed internally to limit their outward extent of movement. This permits a yielding movement necessitated by the angular position of the bus bar mounting with respect to the straight line travel of the die carriage, to maintain a proper engagement from an extreme outward position of the contacts 64 to the limit of inner movement thereof, as the carriage travels along.

The source of power for driving the pulley 31 is, as stated above, the motor 18. This motor is mounted on a shiftable platform 65 which is provided with an adjusting device 66 effective to raise or lower the motor and thus vary the tension placed upon the various belt gearing extending from the motor.

In addition to the pulley 19 which serves to drive the fly wheel pulley 16, there is a second pulley 67 on the motor shaft which actuates or drives a belting 68. The belt 68 passes over angularly related idler pulleys 69 and 70 around the corner of the frame of the machine to the pulley 31.

From the foregoing it will be noted that while the motor 18 furnishes all the power in the illustrated embodiment, for operating the entire machine, that because of the magnetic clutch 36-38, and the control thereof, the paper feed drive is independent and distinct from any other machine operation, and is under a separate and independent control. This is just as true as though there were no self-containing source of power such as the motor 18 in the machine at all, as would be the case were the fly wheel pulley 16 driven from an over head factory belt gearing system, and the paper feed mechanism driven from a separate motor, or from a central source of power in a factory.

Die inking mechanism

The mechanism for applying ink to the marking elements of the die unit is best illustrated in Figs. 1, 2, 5 and 6. In order to apply ink to the marking elements of the die there is provided an inking mechanism including a main ink roll 73, mounted adjustably in brackets 74. The adjustable mounting is similar to that in application, Serial No. 83,796, and consists in a spring arrangement 75 below the roll shaft and an adjusting screw 76 above. Between the spring 75 and the adjusting screw 76, on each bracket 74, is a bearing box 77 which receives the shaft or studs 78 for the roll 73, and with this arrangement, the level of the roll 73 can be varied at either or both ends of the roll, to ensure even application of ink to the marking elements of the die.

The brackets 74 also carry adjustable arms 79 which in turn support a distributor roll 80 (Fig. 5). An adjusting device 81 serves to regulate the pressure between the main roll 73 and the distributor roll 81.

The brackets 74 are supported upon a shaft 82 which is mounted for adjustment from the front of the machine as more completely shown in application, Serial No. 83,796, to accommodate the desired pressure of the roll 73 against the die, that is for light or heavy marking. This adjustment includes a rod or link (not shown) which extends to an adjusting knob and dial 84 at the front of the machine.

To facilitate removal or replacement of the main roll 73, the stud 78 at one end of the roll is made separate from the roll, fitting into a recess in the end of the roll. This stud is connected to a knob or handle 85 (Fig. 6) and is normally urged by a spring 86 into engagement with the roll 73. When it is desired to remove the roll, simply pulling the handle 85 endwise will withdraw the stud 78, and the roll can be slipped out of the other bracket.

An ink pad or supply trough 88, arranged to furnish ink to the main ink roll 73 is pivotally mounted at 89 to the brackets 74, being normally spaced slightly from the main roll 73 but

movable into engagement therewith. A leaf spring 90 secured to the movable trough or pad 88 projects into the path of the plunger 12, whereupon with each stroke of the plunger the trough will be kicked upwardly into engagement with the ink applying roll and thereby replenish the ink on the roll.

A better application of ink to the roll, and from the roll to the die is provided if the roll is driven or rotated, and to effect this drive, 10 there is provided a belt 91 (Fig. 2) which is secured to a pin 92 on the die carriage. The belt passes over suitable guide pulleys and idler pulleys in the machine frame, and over idler pulleys 93-93 on one of the brackets 74, into engagement with a driving pulley 94 rigid with one of the studs 78 for the roll 73. As illustrated, it is on the endwise movable stud, but obviously could be located at the other end of the roll. Accordingly, as the carriage moves forwardly and backwardly, the belt 91 will be actuated, and the roll will be rotated.

It is contemplated that the entire inking mechanism, due to its pivotal mounting, will be effective only on the forward or outward stroke 20 of the die carriage, and will be controlled by a cam mechanism as fully described in application, Serial No. 83,796, such mechanism including the cam 156, hereinafter referred to, in connection with the carriage drive mechanism.

Control linkages for the driving units

The controls by means of which the driving mechanism and other operating parts of the 35 machine are set in operation are best illustrated in Figs. 1 to 4. The crank 17 for the plunger 12, carries the main fly wheel, extending for that purpose through the side of the frame 10. This fly wheel has a hub portion forming a pulley, 40 as shown at 96 (Fig. 1), and between the hub 96 and the frame 10 is the usual clutch hub 97 (Fig. 2) carrying the clutch driving key 98 which is spring urged toward the hub 96, being restrained, however, by a wedge arm 100, pivoted 45 to the frame of the machine at 101. The hub 96 is recessed on the face opposite the clutch hub 97, and positioned in the recessed portion is a hardened pin 103. When the wedge is withdrawn by a dog arm 99 from the path of key 98, 50 the key is projected into the recess, and will engage the hardened pin 103 and serve to drive the crank shaft for a single revolution. This structure just described is substantially the same as disclosed in the patents and applications mentioned above.

The clutch hub 97 is slightly cam shaped, being provided with a high point 104.

The single treadle 106 of the machine is connected by means of links 107 and 108 through a kick-off mechanism indicated generally at 109 to a bar 110 mounted for limited sliding movement at the top side of the frame 10. The kick-off mechanism 109 and the treadle arrangement 65 are substantially the same, as described in the patents and applications above mentioned.

The bar 110 is in turn pivotally connected to a link 111, which is pivoted to a rocker arm 112. This rocker arm controls movement of a shaft 113 for purposes hereinafter described. Through 70 mechanism shown in Figs. 7 to 10, which is controlled by the shaft 113, the movements of the die carriage and other operating parts are controlled. The die carriage, as stated, moves from the rear of the machine to the front when the treadle 106 is actuated, momentarily coming to

rest while the plunger moves through its cycle toward and from the die carriage. When the carriage reaches its forward limit of travel, it trips a rocker arm 83, which through connections to the dog arm 99, withdraws the wedge 100, to permit functioning of the clutch key 98, and the shaft 17 then actuates the plunger 12. These operations take place during a single revolution of the main shaft which actuates the plunger.

Thereafter it is necessary to return the die carriage to its rear or innermost position, in order that fresh work may be placed on the work supporting plunger. To automatically effect the equivalent of a retreading of the machine and thus return the die carriage to its original position, there is an arm 114, pivoted at 115, to the side of the frame 10. A yoke 116 also pivoted at 115 terminates in a roller 117 which rides on the clutch hub 97, and over the high point 104. The yoke 116 and arm 114 are, in effect, a single continuous lever. Movement of the yoke arm as it rides over the high point of the clutch hub cam will be transmitted to the arm 114 through a yielding connection or resilient joint comprising the fingers 118-118 of the yoke 116, and a spring 119 seated in a recess in the arm 114 and projecting therefrom to engage one of the fingers 118. The purpose of this resilient joint is to prevent breakage or injury to the lever 114 in the event that the clutch 97 inadvertently fails to stop after a single revolution, it being evident that if a single rigid connection was established between the clutch and the carriage driving mechanism, and the clutch continued to operate, something would have to give. In the present instance, the resilient joint takes care of the situation. A lost motion connection including a spring mounted guide stud 120 serves to further support the lever 114.

The upper end of the lever 114 carries a roll 121 which rides on a cam 122, which cam serves to return the lever 114 to its original position after it has been actuated by the cam or high point 104. Pivoted to the arm 114 is a link 123 connected to a rocker 124, which rocker is connected to a circuit maker and breaker shown in Figs. 7 to 9, and hereinafter described. When the lever 114 is actuated by the cam 104 it serves through the connections 123 and 124 to complete a circuit for the return stroke of the die carriage, and when the cam 122 returns the lever 114 to its original position, the circuit is broken.

A constantly rotating pulley 125 driven from the fly wheel pulley 16, serves to rotate a shaft 126, which shaft carries an electro-magnetic clutch shown in Fig. 8. A tension spring device 127 serves to keep the bar 110 from excessive vibration and to hold it in place against the frame 10. This spring device also serves the purpose of supplying sufficient friction against the bar 110 to maintain it in any position to which it has been actuated. A similar spring device operating from the side of the housing on the stud 120 performs a similar function for the arm or lever 114.

Carriage driving mechanism

Referring now particularly to Figs. 7, 8 and 9, which illustrate details of the mechanism for driving the die carriage to and from its operative position with respect to the work supporting plunger, it will be seen that the constantly rotating pulley 125 drives a shaft 126, the pulley itself being driven from the fly wheel pulley hub 75

portion 96. The shaft 126 extends through a magnetic clutch 129, finding a bearing in a sleeve 130. The clutch 129 is similar to the clutch 36-38, described in connection with the paper feed, and comprises a clutch face 131 which constantly rotates with the shaft 126. The sleeve 130 carries a second clutch face 132 which, when attracted by the magnetic coil 133, slides into engagement with the clutch facing 131, for actuation thereby. A spring 134 operates between thrust bearings in opposition to the magnetic operations, and normally positions the sleeve 130 away from the rotating portion of the clutch when the coil 133 is not energized. A bracket 135, stationary with the frame or housing of the driving mechanism, indicated at 22, serves to support a brake surface 136. Immediately upon cessation of the magnetic clutch operation, the spring 134 comes into play and pushes the plate 132 against the brake 136, which is of the friction plate type, stopping rotation immediately.

The sleeve 130 terminates at the end opposite the plate 132 in a pinion 137, which obviously will be rotated, when the clutch plates 131 and 132 are in engagement, this pinion meshing with a gear 138 keyed to a shaft 139. The end of the shaft 139 serves to mount the crank arm 140 (see also Fig. 2) which is suitably connected as by a pitman to the die carriage 13. Such connections may be substantially similar to the telescoping arm arrangement shown in Serial No. 83,796. The clutch 129 will be provided with commutator rings 141-141, which receive current from brushes appropriately mounted in the frame 22.

When the machine is treadled the rocker 112 (see also Fig. 1) is rocked, and this rocker, being pinned to shaft 113 oscillates said shaft. A finger 143, pinned to the shaft 113, projects toward a circuit maker and breaker consisting of two flexible contacts 144 and 145 which are normally spaced from each other. When the finger 143 engages the contact 145, it will push it into engagement with the contact 144, as illustrated in Fig. 7, where it will be momentarily held by a cam 157, and this establishes a circuit through the clutch 129, thus actuating the shaft 139, through the gearing 137-138. When this occurs, the crank arm 140 will move the die carriage 13 forwardly.

At the forward limit of its travel the die carriage sets into operation the control linkages for actuating the plunger shaft 17 and the clutch hub 97 carrying the cam or high point 104, as described above.

The cam or high point 104 on the clutch hub 97, through its actuation of the arm 114, and the mechanisms which are set into operation by movement of the arms 114 and 124, and actuation of the magnetic clutch, then move a rocker 146, which is pinned to a shaft 147, and thereby rocks the shaft 147. Also pinned to the shaft 147 is a lever 148 having a T-shaped head 149, positioned to engage two additional circuit makers and breakers 150 and 151, causing them to operate in the manner described for the contacts 144 and 145 of the first circuit maker and breaker.

The switch or circuit maker and breaker 150 re-establishes a circuit through the clutch 129, such circuit having been broken by separation of the contacts 144-145, and the clutch 129 then actuates the crank arm or lever 140 to return the die carriage to its original position. The release of the switch 144-145 is effected by a pin plate 152 on the shaft 39, the pin plate carrying a pin 153, which pin engages a finger 154 integral with the finger 143.

The timing of the actuating mechanism for the switch 151 is such that the switch establishes a circuit to the bus bar mounting 59 on the return stroke only, of the die carriage, and thence through the clutch 36-38 for the paper feed. The switch 151 will be broken or opened on the out-stroke of the die carriage, to insure that there will be no feed of paper until after the ornamenting operation has been completed. The shaft 139 also carries an ink roll cam 156 for depressing the ink roll mechanism on the return stroke of the die carriage, in the customary manner, fully described in the aforementioned patents and application. The pin plate 152 is cam shaped and provides a high area 157, which contacts a block 158 on the contact 145, to hold the contacts 144-145 momentarily together after the finger 143 has receded, thus permitting the carriage 13 to complete its forward movement.

In order to provide adjustments of the circuit makers and breakers, the contacts 144-145 as well as the contacts of the switches 150 and 151 are mounted in a fiber block 159, which block can be raised or lowered, by means of adjusting devices 160. Obviously, the vertical adjustment of the block will cause a change in timing between the block 158 and the cam 157 and this in turn affects the travel of the die carriage since the control and timing of current to the magnetic clutch 129 will be varied by this adjustment.

From the foregoing description, the operation and advantages will be readily apparent. With the die carriage in its rearmost position, inwardly of the frame 10, an operator will position the work on the plunger 12, by reference to the gauges. Upon treading the machine, the die carriage will first move to its outer or forward position, trip the control linkages for the plunger, which will rise to effect the ornamenting operation, and return to a position of rest, due to the action of the single revolution clutch 91. During this movement of the die carriage, the ink roll mechanism, through the action of the cam 156, and associated levers, will be raised to a position where the ink roll will engage the marking elements of the die, and also during the same cycle of operation of the plunger and die carriage the plunger will kick the ink supply pad 88 into engagement with the ink roll 13, to replenish ink thereon. The usual brake mechanism indicated generally at 142 will be effective to bring the parts to rest promptly upon completion of the single revolution of the shaft 17.

After the ornamenting operation has been completed, the die carriage, and the contact bridge 64, through its contact with the bus bar mounting 59 will set the paper feed mechanism into operation, the knife switch 151 being closed at this point in the cycle, thus presenting a fresh portion of the packing material web to the plunger 12, for the next piece of work.

The work will be stripped from the cutters of the die in the same manner or in a similar manner to that described in Patent Reissue 20,294.

With the arrangement of controls for the die carriage and actuating mechanism as described, it is possible to operate the plunger, the carriage, and the paper feed, in fact all moving parts in synchronized relation, and it is possible to operate any one of the carriage, plunger, or paper feed to the exclusion of the other, or to operate the carriage through half of a complete stroke, i. e., outwardly to a forward position and stop, or inwardly to a rear position and stop, either alone or in conjunction with the plunger move-

ment. It is further evident that the machine is designed for cutting or marking per se, or in combination.

The entire construction herein described, is intended to be "fool proof," and the machine operation so simplified, safe and automatic, as to make it possible for a relatively inexperienced operator to operate the machine without difficulty and in a safe manner.

In this connection, it may be found desirable to lock the machine against the possibility of treadling, in order to make various adjustments. Accordingly, a pivoted latch 161 is mounted on the side of the frame, which latch comprises a pivoted plate having a pin 162 which may be swung into the path of a rocker arm forming part of the connections to the bar 110, as shown in Fig. 1. With the latch in the position shown, it will be evident that the treadle 106 is ineffective.

Among the advantages are the need for gauging the work but once for both cutting out and marking operations, the saving in ink required, by light but legible marking, the fact that the present device may be successfully used for marking on all thicknesses and characters of work with the proper degree of pressure for printing, the attainment of uniform marking of various thicknesses and characters of material, in a uniform manner, the extremely accurate control and regulation of the several mechanisms, etc.

Furthermore, all of the advantages of ink marking over straight indentation or impression marking, or other types of marking, as fully set out in the patents upon which this case represents improvements, are attained, these advantages being well recognized at the present time.

It will be understood that this description is intended as illustrative and that the invention is not to be limited thereby, other than as defined in the appended claims. By way of example, the die may be arranged to cut upwardly instead of downwardly, the pressures might be applied from above instead of below the work, the paper feed might be driven from an entirely separate motor or other source of power than the motor 18; the machine might be operated from a different source than the motor 18, which could be used solely for the paper feed, in fact many modifications may occur to those skilled in the art.

Having thus described my invention what I claim as new and desire to secure by Letters Patent of the United States is:

1. In an ornamenting machine of the class described, a die, reaction means opposed thereto, means to produce a relative movement between said die and said reaction means whereby to effect an ornamenting operation upon a work piece interposed therebetween, means to feed a web of backing material between said die and reaction means adjacent a plane of the work piece, and means to actuate said feed means independently of the operation of said means for producing relative movement.

2. In an ornamenting machine of the class described, a die, reaction means opposed thereto, means to produce a relative movement between said die and said reaction means whereby to effect an ornamenting operation upon a work piece interposed therebetween, means to feed a web of backing material between said die and reaction means adjacent a plane of the work piece, means to actuate said feed means inde-

pendently of the operation of said means for producing relative movement, and means to synchronize the movements of said feed means with the relative movement between said die and reaction means.

3. In an ornamenting machine of the class described, having operating parts for effecting an ornamenting operation on a piece of work, and means for feeding a web of backing material adjacent the work, the combination of means to actuate said operating parts, and independent means to actuate said feed means.

4. In an ornamenting machine of the class described, having operating parts for effecting an ornamenting operation on a piece of work, and means for feeding a web of backing material adjacent the work, the combination of means to actuate said operating parts, independent means to actuate said feed means, and means controlled by one of said operating parts for controlling the operation of said feed means.

5. In an ornamenting machine of the class described having operating parts for effecting an ornamenting operation on a piece of work, and means for feeding a backing material adjacent the work, the combination of means to actuate said operating parts, and means to actuate said feed means independently of said operating parts.

6. In an ornamenting machine of the class described, having operating parts for effecting an ornamenting operation on a piece of work, and means for feeding a web of backing material adjacent the work, the combination of means to actuate said operating parts, independent means to actuate said feed means, a common source of power for actuating said operating parts and said feed means and control means for said feed means whereby said feed means will operate independently of said operating parts.

7. In an ornamenting machine of the class described, the combination with a die and means to produce a relative movement between said die and a piece of work supported in said machine, of means to feed backing material across the path of said relative movement between the die and work, and means to operate said feed means separately and independently of the operation of any of the working parts.

8. In an ornamenting machine of the class described, a work support, a die carriage mounted for movement into and out of an operative position relative to said work support, means to feed a web of backing material intermittently therebetween, means to produce a relative movement between said die carriage and work support to effect an ornamenting operation on a piece of work positioned on said support, means to synchronize the operations of the feed means, the die carriage, and the relative movement between the carriage and work support, and means to actuate the feed means independently of the operations of the work support and carriage.

9. In an ornamenting machine of the class described, a work support, a die carriage mounted for lateral movement into and out of an operative position relative to said work support, a die unit carried by said carriage having a printing element and a cutting element thereon, means to apply ink to the printing element during the lateral movement of said die carriage, means to produce a relative movement between said die and work support to effect an ornamenting operation on a piece of work positioned on

said support, means to feed a web of backing material intermittently across said work support, at the opposite side of the work from the die, and means to actuate said feed means independently of the operations of the die carriage, the die, and the work support.

10. Backing material feed means for performing machines having operating parts, comprising a drive shaft, and means to actuate the same, 10 a feed roll and means to actuate the same, a magnetic clutch interposed between said drive shaft and said actuating means for the feed roll, and means for controlling the operation of said magnetic clutch to actuate said feed roll independently of and in predetermined relation to the actuation of said operating parts.

11. In an ornamenting machine of the class described, a work support, a die carriage mounted for lateral movement into and out of an operative position relative to said work support, 20 means for actuating said die carriage comprising a drive shaft, driven connections to said carriage, and an electro-magnetic clutch between said drive shaft and driven connections.

12. In an ornamenting machine of the class described, a work support, a die carriage mounted for lateral movement into and out of operative position relative to said work support, means for actuating said die carriage comprising a constantly rotating drive shaft, driven connections to said carriage, an electro-magnetic clutch between said drive shaft and driven connections, and operator controlled means for initiating movement of said carriage in one direction, and 35 automatically controlled means synchronized with movements of other operating parts of the machine for initiating movement of said carriage in a reverse direction.

13. In an ornamenting machine of the class 40 described, a work support, a die carriage mounted for lateral movement into and out of operative position relative to said work support, drive means for said carriage including an electro-magnetic clutch, means for feeding a backing 45 material across said work support, actuating means therefor, including a second magnetic clutch, a switch for controlling the circuit through the carriage drive clutch, and means for controlling said switch to actuate said carriage in one direction, a second switch for re-establishing the circuit through the carriage drive clutch to actuate said carriage in a reverse direction, and automatic means for controlling the operation thereof, a third switch for controlling the circuit through the clutch of said feed 50 means, and means for controlling said switch in timed relation to the operation of said first two switches.

14. In an ornamenting machine of the class 60 described, a work support, a die carriage mounted for lateral movement into and out of operative position relative to said work support, drive means for said carriage including an electro-magnetic clutch, means for feeding a backing material across said work support, actuating means therefor, including a second magnetic clutch, a switch for controlling the circuit through the carriage drive clutch, and means for controlling said switch to actuate said carriage in one direction, a second switch for re-establishing the circuit through the carriage drive clutch to actuate said carriage in a reverse direction, and automatic means for controlling the operation thereof, a third switch for controlling the circuit through the clutch of said 65 70 75

feed means, and carriage controlled means for controlling said third switch including circuit making and breaking means between the carriage and a lead to said feed means clutch.

15. In an ornamenting machine of the class described, a work support, a die carriage mounted for lateral movement into and out of an operative position relative to said work support, a die unit carried by said carriage having a printing element, means to apply ink to the printing element during the movement of said carriage comprising a rotatable ink applying roll, and means connecting said carriage and said roll to rotate the latter during movement of said carriage.

16. In an ornamenting machine of the class described, a reciprocable plunger, a die positioned in opposed relation thereto, a printing element in said die, means to apply ink to said printing element, ink supply means for replenishing the ink in said ink applying means, said ink supply means comprising a member movable to and from said ink applying means and having a portion extending in the path of movement of said plunger for engagement by the plunger during movement thereof, whereby it will be engaged by the plunger and moved into engagement with the ink applying means upon each stroke of the plunger in one direction, and retracted therefrom during movement of the plunger in the opposite direction.

17. In an ornamenting machine of the class described, a reciprocable plunger, a die positioned in opposed relation thereto, a printing element in said die, an ink roll for applying ink to said printing element, an ink supply means for replenishing the ink on said roll, said supply means comprising a plate pivoted adjacent said roll for movement into and out of engagement therewith, said plate having a finger extending into the path of movement of said plunger whereby said plunger will engage the finger and move the supply plate against the ink roll upon a stroke in one direction, said supply plate being mounted to move by gravity away from said roll during movement of the plunger in the opposite direction.

18. Ink applying means for marking dies in a marking machine, comprising a rotatable ink supply roll, and means to rotate same, a releasable stud at one end of said roll, and means to release said stud for removal of the roll, a pair of brackets in which said roll is mounted, and adjustable bearing blocks in each bracket supporting the ends of said roll, means to move said roll into the plane of the marking elements on the marking die at a predetermined point in the cycle of operations of the machine, and means to apply ink to said roll at a predetermined point in each cycle of operations, to replenish the supply of ink on said roll.

19. In an ornamenting machine of the class described, a reciprocable plunger, a die carriage movable laterally with respect to said plunger, and means for actuating said plunger and die carriage in synchronized relation comprising an electrically actuated driving mechanism effective to move said die carriage laterally from an inoperative position to an operative relation with respect to said plunger, and mechanism for reciprocating said plunger toward and from said carriage, circuit making and breaking means controlled by said carriage when in its operative position to automatically initiate actuation of said plunger, and circuit making and breaking

means controlled by the plunger actuating mechanism for initiating actuation of said die carriage to an inoperative position upon completion of the plunger movement.

5 20. In an ornamenting machine of the class described, a reciprocable work support, a die carriage movable laterally with respect to said support, means to feed a web of backing material across said support, and means for actuating said support, said die carriage, and said feed means in synchronized relation comprising a driving mechanism effective to move said die carriage laterally from an inoperative position to an operative position with respect to said support, mechanism for reciprocating said support toward and from said carriage, and independent mechanism for driving a feed roll in said feed means; means controlled by said carriage, when it reaches an operative position, to automatically initiate actuation of said support reciprocating mechanism, means controlled by the support reciprocating mechanism for initiating actuation of said die carriage to an inoperative position upon completion of the support movement, and means controlled by said carriage through a portion of its movement for initiating actuation of said feed roll driving mechanism.

20 21. In an ornamenting machine of the class described, a die, reaction means opposed thereto, means to produce a relative movement between said die and said reaction means whereby to effect an ornamenting operation upon a work piece interposed therebetween, means to feed a web of backing material between said die and reaction means adjacent a plane of the work piece, means to actuate said feed means independently of the operation of said means for producing relative movement, and means to adjust the period of actuation of said feed means, to vary the amount of backing material fed.

25 22. In an ornamenting machine of the class described, a die, reaction means opposed thereto, means to produce a relative movement between said die and said reaction means whereby to effect an ornamenting operation upon a work piece interposed therebetween, means to feed a web of backing material between said die and reaction means adjacent a plane of the work piece, means to actuate said feed means independently of the operation of said means for producing relative movement, and means to vary the timing of the feed means actuation relative to the timing of the operation of the means for producing relative movement.

30 23. In an ornamenting machine of the class described, a die, reaction means opposed thereto, means to produce a relative movement between said die and said reaction means whereby to effect an ornamenting operation upon a work piece interposed therebetween, means to feed a web of backing material between said die and reaction means adjacent a plane of the work piece, means to actuate said feed means independently of the operation of said means for producing relative movement, means to synchronize the movements of said feed means with the relative movement between said die and reaction means, and means to vary the synchronization of said movements.

35 24. In an ornamenting machine of the class described, a die, reaction means opposed thereto, means to produce a relative movement between said die and said reaction means whereby to effect an ornamenting operation upon a work piece interposed therebetween, means to feed a

web of backing material between said die and reaction means adjacent a plane of the work piece, means to actuate said feed means independently of the operation of said means for producing relative movement, means to synchronize the movements of said feed means with the relative movement between said die and reaction means, and means to adjust the period of actuation of said feed means, to vary the amount of backing material fed.

25. In an ornamenting machine of the class described, a die, reaction means opposed thereto, means to produce a relative movement between said die and said reaction means whereby to effect an ornamenting operation upon a work piece interposed therebetween, means to feed a web of backing material between said die and reaction means adjacent a plane of the work piece, means to actuate said feed means independently of the operation of said means for producing relative movement, means to synchronize the movements of said die means with the relative movement between said die and reaction means, and means to adjust the period of actuation of said feed means, to vary the amount of backing material fed, and at the same time create a different synchronized relation between said movements.

26. In an ornamenting machine of the class described, having operating parts for effecting an ornamenting operation on a piece of work, means for feeding a web of backing material adjacent the work, the combination of means to actuate said operating parts, independent means to actuate said feed means, and means to adjust the period of actuation of said feed means, to vary the amount of backing material fed.

27. In an ornamenting machine of the class described, having operating parts for effecting an ornamenting operation on a piece of work, means for feeding a web of backing material adjacent the work, the combination of means to actuate said operating parts, independent means to actuate said feed means, and means to vary the timing of the feed means actuation relative to the timing of the movements of said operating parts.

28. In an ornamenting machine of the class described, having operating parts for effecting an ornamenting operation on a piece of work, means for feeding a web of backing material adjacent the work, the combination of means to actuate said operating parts, independent means to actuate said feed means, means controlled by one of said operating parts for controlling the operation of said feed means, and means to adjust the period of actuation of said feed means, to vary the amount of backing material fed.

29. In an ornamenting machine of the class described, having operating parts for effecting an ornamenting operation on a piece of work, means for feeding a web of backing material adjacent the work, the combination of means to actuate said operating parts, independent means to actuate said feed means, means controlled by one of said operating parts for controlling the operation of said feed means, and means to vary the timing of the feed means actuation relative to the timing of the movements of said operating parts.

30. In an ornamenting machine of the class described having operating parts for effecting an ornamenting operation on a piece of work, means for feeding a backing material adjacent the work, the combination of means to actuate

said operating parts, means to actuate said feed means independently of said operating parts, and means to adjust the period of actuation of said feed means, to vary the amount of backing material fed.

31. In an ornamenting machine of the class described having operating parts for effecting an ornamenting operation on a piece of work, means for feeding a backing material adjacent the work, the combination of means to actuate said operating parts, means to actuate said feed means independently of said operating parts, and means to vary the timing of the feed means actuation relative to the timing of the movements of said operating parts.

32. In an ornamenting machine of the class described, the combination with a die and means to produce a relative movement between said die and a piece of work supported in said machine, of means to feed backing material across the path of said relative movement between the die and work, means to operate said feed means separately and independently of the operation of any of the working parts, and means to adjust the period of actuation of said feed means, to vary the amount of backing material fed.

33. In an ornamenting machine of the class described, the combination with a die and means to produce a relative movement between said die and a piece of work supported in said machine, of means to feed backing material across the path of said relative movement between the die and work, means to operate said feed means separately and independently of the operation of any of the working parts, and means to vary the timing of the feed means actuation relative to the timing of the movements of said operating parts.

34. In an ornamenting machine of the class described, a work support, a die carriage mounted for movement into and out of an operative position relative to said work support, means to feed a web of backing material intermittently therebetween, means to produce a relative movement between said die carriage and work support to effect an ornamenting operation on a piece of work positioned on said support, means to synchronize the operations of the feed means, the die carriage, and the relative movement between the carriage and work support, means to actuate the feed means independently of the operations of the work support and carriage, and means to adjust the period of actuation of said feed means, to vary the amount of backing material fed.

35. In an ornamenting machine of the class described, a work support, a die carriage mounted for movement into and out of an operative position relative to said work support, means to feed a web of backing material intermittently therebetween, means to produce a relative movement between said die carriage and work support to effect an ornamenting operation on a piece of work positioned on said support, means to synchronize the operations of the feed means, the die carriage, and the relative movement between the carriage and work support, means to actuate the feed means independently of the operations of the work support and carriage, and means including said carriage, and a member in said machine cooperative with said carriage and adjustable relative to said carriage, to vary the period of actuation of said feed means, and thereby vary the amount of backing material fed.

36. In an ornamenting machine of the class described, a work support, a die carriage mounted

for movement into and out of an operative position relative to said work support, means to feed a web of backing material intermittently there-between, means to produce a relative movement between said die carriage and work support to effect an ornamenting operation on a piece of work positioned on said support, means to synchronize the operations of the feed means, the die carriage, and the relative movement between the carriage and work support, means to actuate the feed means independently of the operations of the work support and carriage, and means to vary the timing of the feed means actuation relative to the timing of the operation of the means for producing said relative movement.

37. Backing material feed means for perforating machines having operating parts, comprising a drive shaft, and means to actuate the same, a feed roll and means to actuate the same, a magnetic clutch interposed between said drive shaft and said actuating means for the feed roll, means for controlling the operation of said magnetic clutch to actuate said feed roll independently of and in predetermined relation to the actuation of said operating parts, and means to adjust the period of actuation of said feed roll, to vary the amount of backing material fed.

38. Backing material feed means for perforating machines having operating parts, comprising a drive shaft, and means to actuate the same, a feed roll and means to actuate the same, a magnetic clutch interposed between said drive shaft and said actuating means for the feed roll, means for controlling the operation of said magnetic clutch to actuate said feed roll independently of and in predetermined relation to the actuation of said operating parts, and means to vary the timing of the feed means actuation relative to the timing of the movements of said operating parts.

39. Backing material feed means for perforating machines having operating parts, comprising a drive shaft, and means to actuate the same, a feed roll and means to actuate the same, a magnetic clutch interposed between said drive shaft and said actuating means for the feed roll, means for controlling the operation of said magnetic clutch to actuate said feed roll independently of and in predetermined relation to the actuation of said operating parts, and means, including an electric contact cooperative with one of said operating parts, and adjustable with respect to said part, effective to adjust the period of actuation of said feed roll, and thereby vary the amount of backing material fed.

40. In an ornamenting machine of the class described, a work support, a die carriage mounted for lateral movement into and out of an operative position relative to said work support, means for actuating said die carriage comprising a drive shaft, driven connections to said carriage, an electro-magnetic clutch between said drive shaft and driven connections, means to feed a backing material for a die on said carriage, in synchronized relation to the carriage, and adjustable means extending at least partially along the path of said die carriage, and engageable with a contact on said die carriage during part of its travel, effective to adjust the period of operation of said paper feed means.

41. In an ornamenting machine of the class described, a work support, a die carriage mounted for lateral movement into and out of an operative position relative to said work support, a die unit carried by said carriage having a printing ele-

ment, means to apply ink to the printing element during the movement of said carriage comprising a rotatable ink applying roll, means connecting said carriage and said roll to rotate the latter during movement of said carriage, and means to replenish ink on said roll during each cycle of operations of the machine.

42. In an ornamenting machine of the class described, a movable work support, a die carriage mounted for lateral movement into and out of an operative position relative to said work support, a die unit carried by said carriage having a printing element, means to apply ink to the printing element during the movement of said carriage comprising a rotatable ink applying roll, means connecting said carriage and said roll to rotate the latter during movement of said carriage, an ink supply means for replenishing ink on said roll, positioned adjacent said roll, and means connected to said ink supply means and positioned in the path of movement of said work support for engagement thereby, effective to move said ink supply means bodily into engagement with said roll upon movement of said work support.

43. Ink applying means for marking dies in a marking machine, comprising a rotatable ink supply roll, and means to rotate same, a releasable stud at one end of said roll, and means to release said stud for removal of the roll, a pair of brackets in which said roll is mounted, and adjustable bearing blocks in each bracket supporting the ends of said roll, means to move said roll into the plane of the marking elements on the marking die at a predetermined point in the cycle of operations of the machine.

44. Ink applying means for marking dies in a marking machine, comprising a rotatable ink supply roll, and means to rotate same, a releasable stud at one end of said roll, and means to release said stud for removal of the roll, a pair of brackets in which said roll is mounted, and adjustable bearing blocks in each bracket supporting the ends of said roll, means to move said roll into the plane of the marking elements on the marking die at a predetermined point in the cycle of operations of the machine, a distributor roll engageable with said ink supply roll, effective to distribute ink evenly over said latter roll, and means to regulate the pressure between said rolls.

45. Ink applying means for marking dies in a marking machine, comprising a rotatable ink supply roll, and means to rotate same, a releasable stud at one end of said roll, and means to release said stud for removal of the roll, a pair of brackets in which said roll is mounted, and adjustable bearing blocks in each bracket supporting the ends of said roll, means to move said roll into the plane of the marking elements on the marking die at a predetermined point in the cycle of operations of the machine, and means to adjust said bearing blocks to vary the level of said roll at either end, thereby to insure even application of ink to the marking elements of the marking die.

46. In an ornamenting machine of the class described having operating parts for effecting an ornamenting operation on a piece of work, including a pressure applying plunger, and means for feeding a web of backing material adjacent the work, the combination of means to drive the plunger, means to drive the web feeding means, and means to operate one of said driving means independently of the other.

47. In an ornamenting machine of the class

described having operating parts for effecting an ornamenting operation on a piece of work, including a pressure applying plunger, and means for feeding a web of backing material adjacent the work, the combination of means to drive the plunger, means to drive the web feeding means, means to operate one of said driving means independently of the other, and a common source of power for both drive means.

48. In an ornamenting machine of the class described, a work support, a die carriage mounted for lateral movement into and out of an operative position relative to said work support, means for actuating said die carriage comprising a drive shaft, driven connections to said carriage, electric clutch means between said drive shaft and driven connections, and control means for said clutch effective to bring said die carriage to rest at the same predetermined point in successive movements to operative position.

49. In an ornamenting machine of the class described, a work support, a die carriage mounted for lateral movement into and out of an operative position relative to said work support, means for actuating said die carriage comprising a drive shaft, driven connections to said carriage, electric clutch means between said drive shaft and driven connections, control means for said clutch effective to bring said die carriage to rest at the same predetermined point in successive movements to operative position, and adjustable electric means for varying said predetermined point.

50. In an ornamenting machine, a work support, a cutting die mounted for movement into and out of aligned cutting position relative to said work support, and electrically actuated driving mechanism connected to move said die into and out of cutting position, and automatic means to control the timing of the flow of current to said driving mechanism whereby to bring said die to rest in exactly the same aligned cutting position, for successive cutting operations.

51. In an ornamenting machine, a work support, a cutting die mounted for movement into and out of aligned cutting position relative to said work support, and electrically actuated driving mechanism connected to move said die into and out of cutting position, including clutch means effective to bring said die to rest in its aligned cutting position, and electric means automatically operable to actuate said clutch

means whereby to bring said die to rest in exactly the same aligned cutting position for successive cutting operations.

52. In an ornamenting machine, a work support, a cutting die mounted for movement into and out of aligned cutting position relative to said work support, and electrically actuated driving mechanism connected to move said die into and out of cutting position, including clutch means effective to bring said die to rest in its aligned cutting position, and electric means automatically operable to actuate said clutch means whereby to bring said die to rest in exactly the same aligned cutting position for successive cutting operations, and thereafter to actuate said clutch means to return the die to an inoperative position.

53. In an ornamenting machine, a work support, a die mounted for movement into and out of aligned operating position relative to said work support, driving mechanism for said die including clutch means effective to bring said die to rest in its aligned operating position, electric means automatically operable to actuate said clutch means so as to bring said die to rest in exactly the same aligned operating position for successive operations, and means to adjust said automatic electric means whereby to vary the predetermined operating position of rest.

54. In an ornamenting machine, a work support, a die mounted for movement into and out of aligned operating position relative to said work support, and electrically actuated driving mechanism connected to move said die unit into and out of aligned position, automatic means to control the timing of the flow of current to said driving mechanism whereby to bring said die to rest in the same aligned operating position, for successive operations, and adjustable means to vary the timing of the flow of current to said driving mechanism whereby to vary the predetermined point of rest.

55. In an ornamenting machine, a work support, a die mounted for movement into and out of aligned operating position relative to said work support, driving mechanism to actuate said die including an electro-magnetic clutch, and electric circuit making and breaking means for said clutch, effective through said clutch to bring said die to rest at the same predetermined point of alignment.

BENJAMIN W. FREEMAN.
